UNITED STATES PATENT OFFICE.

ELWOOD B. AYRES, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRIER.

Application filed March 22, 1920. Serial No. 367,838.

To all whom it may concern:

Be it known that I, ELWOOD B. AYRES, a citizen of the United States, residing in Philadelphia, Pennsylvania, have invented 5 certain Improvements in Driers, of which the following is a specification.

My invention relates to certain improvements in machines for drying pottery and like articles.

- 10 One object of my invention is to provide a machine in which material to be dried is carried by an endless conveyer through a drying compartment while subjected to heated air in circulation, the conveyer passing through a cooling compartment after the material being dried has been removed therefrom so as to cool the trays on which the material is to be conveyed after each 15 passage through the drying compartment.
- 20 A further object of the invention is to construct a drying machine so that the endless conveyer will pass alternately over guide wheels at the top and bottom of the drying compartment in order that a large 25 number of trays may be accommodated in a comparatively short drying compartment.

Another object of the invention is to construct the drying chamber so that the air can be circulated transversely through the chamber, while the material is traveling longitudinally therethrough.

A still further object of the invention is to provide a machine in which the material may be subjected to different degrees 35 of heat, and also to provide a machine in which the material is subjected to currents of cool air before being discharged from the machine.

These objects I attain in the following 40 manner, reference being had to the accompanying drawings, in which:

Fig. 1 is a side view of one form of apparatus illustrating my invention.

Fig. 2 is a transverse sectional view on 45 the line 2—2, Fig. 1; and

Fig. 3 is a sectional plan view on the line 3—3, Fig. 1.

Figs. 1, 2 and 3 represent a double drying machine, in which the drying compartments are arranged side by side and separated by a central longitudinal partition 3. 50 The compartments are enclosed within a casing 1 of the ordinary construction. The

drying compartments are defined by partitions 18—17—20, as hereafter more particularly described, the side walls of the compartments being formed by the outer side walls of the casing 1 and the partition 3. In each drying compartment is a partition 5 having openings 6 and 7 for the circulation of air. There may be any number of these openings, depending considerably upon the length of the machine. In each opening 6 is a fan 8 mounted on a shaft 9 extending to the outside of the casing 1. The shaft may be driven by any suitable means. Heating pipes are located at any convenient point so that the air in circulation will be properly heated. In the present instance, these pipes are located back 70 of the partition 5, as clearly shown in Fig. 2. In the specific structure shown, the partition 5 may be said to provide the drying compartment with a drying chamber 2 and a heating chamber in which the heating 75 pipes 4 are located, and said chambers also serve respectively as a diffusing chamber and a return air duct within the drying compartment, the air in circulation traveling in a definite circuit as indicated by 80 the arrows in Fig. 2.

10 is an endless conveyer shown in diagram in Fig. 1. In the present instance suspended from the conveyer are trays 11 pivoted at 12 so that the bottom of each 85 tray is always in a horizontal plane.

In Fig. 1, I have shown the drying compartment and the chamber 2 subdivided by vertical partitions 19 extending transversely across the compartment. In the present instance, these partitions extend from the roof of the casing to a point near the lower guide wheels around which the conveyer passes. The drying compartment is separated from a cooling compartment with its cooling chamber 2^a by a partition 20, and a vertical partition 22, similar to the partition 19, divides the cooling compartment into a large and a small section. At the front end of the drying machine is a narrow compartment 2^b and at the opposite end is a narrow compartment 2^c through which the conveyer extends. In the bottom of the drying machine is a cooling channel, 16, which communicates with the cooling chamber 2^a and also with the section 2^b at the 95 100 105

forward end of the machine. Located at given intervals throughout the length of the drier at the upper portion thereof is a series of guide wheels 13 and alternating with these guide wheels is a series of lower guide wheels 14. The conveyer 10 passes around these two guide wheels so that it travels through the drying compartment and the cooling compartment in a vertical direction. At each end of the machine are guide wheels 15, the guide wheel 15 at the forward end of the machine being located outside of the casing, in the present instance, and the guide wheel 15 at the discharge end of the machine being located within the chamber 2^a. These guide wheels are so located that the return run of the conveyer will travel through the cooling channel, 16, as clearly shown in Fig. 1. As will readily be seen from the drawings, the path traversed by the endless conveyer within the inclosure is circuitous.

The cooling channel 16 is separated from the drying chamber by a horizontal partition 17. This partition stops at the vertical partition 20 and the cooling channel 16 communicates with the cooling chamber 2^a, as shown. One or more of the shafts in which the upper wheels are mounted may be used as driving shafts, as clearly shown in Fig. 2, and the conveyer is loaded at the forward end of the machine, as at a, the tray being designed to receive the articles to be dried. It will be seen that by the U-shaped partition unit comprising partitions 18-17-20, a space or section of the machine is divided off from the rest of the machine including cooling channel 16, and within said space or section thus divided off the air is heated and circulated and the drying operation performed, and

it is to this heating or drying section that the circulation of heated air is confined.

As the conveyer passes through the drying chamber 2, the fans 8 circulate the heated air through two subdivisions thereof and, if desired, the air in one of said two subdivision may be heated to a greater degree than the air in the other. Then the conveyer passes into the cooling chamber 2^a, in the present instance, so as to reduce the temperature of the articles being dried and also to reduce the temperature of the trays carrying the articles. After the articles have been removed through the opening indicated at b at the discharge end of the machine, the conveyer, with the empty trays, passes through the cooling channel, 16, so that when the trays reach the loading point they are cooled sufficiently to receive the articles to be dried.

I claim:

The combination in a drying machine, of a casing; a drying compartment made in two sections; means for circulating air in each section; a series of vertical partitions extending to the top of the casing; a horizontal partition near the bottom of the machine separating the drying compartment from a cooling chamber; a cooling chamber at one end of the machine; means for circulating air therein, the latter cooling chamber communicating with the first mentioned cooling chamber; an upper and lower set of wheels, the lower wheels alternating with the upper wheels; and a conveyer passing around the several wheels and through the two drying compartments and the cooling chamber, the return run of the conveyer passing through the lower cooling chamber.

ELWOOD B. AYRES.
